UNITED STATES PATENT OFFICE

WALTER BAETZ, OF NEW YORK, N. Y., ASSIGNOR TO MAN-O-LAMP CORPORATION, A CORPORATION OF NEW YORK

DESIGN FOR A PICTURE FRAME

Application filed March 1, 1933. Serial No. 47,363. Term of patent 3½ years.

To all whom it may concern:

Be it known that I, WALTER BAETZ, a subject of the King of Great Britain, and a resident of New York, in the county of New York and State of New York, have invented a new, original, and ornamental Design for Picture Frames, of which the following is a specification, reference being had to the accompanying drawing, forming a part hereof.

In the drawing the single figure is a front perspective view illustrating the picture frame from one side. The frame is alike front and rear.

I claim:

The ornamental design for a picture frame substantially as shown and described.

WALTER BAETZ.
